*Primary Examiner—Wallace R. Burke**Assistant Examiner—Freda S. Nunn**Attorney, Agent, or Firm—Banner, Birch, McKie & Beckett***[57] CLAIM****The ornamental design for an electronic computer, as shown and described.****DESCRIPTION**

FIG. 1 is a top, front and right side perspective view of an electronic computer showing my new design;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof;
 FIG. 7 is a bottom plan view thereof; and,
 FIG. 8 is a top, front and right side perspective view thereof in closed position.

FIG. 1
